UNITED STATES PATENT OFFICE

AL ECKSTEIN, OF FAR ROCKAWAY, NEW YORK

DESIGN FOR A COMBINATION NIGHTGOWN AND PAJAMAS OR SIMILAR ARTICLE

Application filed July 25, 1930. Serial No. 36,477. Term of patent 7 years.

To all whom it may concern:

Be it known that AL ECKSTEIN, citizen of the United States, and resident of Far Rockaway, in the county of Queens and State of New York, has invented a new, original, and ornamental Design for Combination Nightgown and Pajamas or Similar Article, of which the following is a specification, reference being had to the accompanying drawing, forming part thereof, in which—

Fig. 1 is a perspective view of combination nightgown and pajamas embodying my invention showing the position thereof when worn; and

Fig. 2 is a perspective view of combination nightgown and pajamas with parts

thereof folded back and the pants portions spread outwardly.

The portion of the rear side of the garment shown in Fig. 2 discloses such features of the design as appear on said rear portion; the portion of the rear side hidden from view in said figure containing no material elements of the design, other than shown in said figure.

I claim:

The ornamental design for a combination nightgown and pajamas or similar article, substantially as shown and described.

Dated, New York city, July 24, 1930.

AL ECKSTEIN.
